UNITED STATES PATENT OFFICE.

CHARLES HOLLAND, OF CHICAGO, ILLINOIS.

HYDROCARBON-FURNACE.

SPECIFICATION forming part of Letters Patent No. 239,785, dated April 5, 1881.

Application filed May 22, 1880. (No model.)

To all whom it may concern:

Be it known that I, CHARLES HOLLAND, of the city of Chicago, in the county of Cook, in the State of Illinois, have invented a new and useful Hydrocarbon-Furnace; and I do hereby declare the following to be a sufficiently full, clear, and exact description thereof to enable others skilled in the art to make and use the said invention.

10 This invention is specially applicable to locomotive-engines, steam fire-engines, and engines for marine propulsion, furnaces for the treatment of ores and metals, and situations where, in the application of heat, sparks or 15 ashes or other deposit of residuum from the fuel is objectionable, and also wherever lightness and compactness of fuel are desired, and is advantageous in being easily and instantly controlled and regulated, and requiring no labor in stoking or firing.

The nature of this invention may be briefly stated to consist in first passing steam or water into heated vessels or retorts, from which it issues at a high temperature and passes into 25 combining-tubes with a current of oil, which it carries with it and delivers in a second series of retorts, discharging their products of distillation into a series of pipes, as shown in the drawings annexed and described in this 30 specification, and embracing, among other features, a series of separate retorts connected by tubes and secured in position in the furnace, so that all surfaces are susceptible of inspection and less liable to strains from local 35 contraction and expansion of parts than the retorts formed of several chambers in one casting, such as are set forth in my Letters Patent No. 203,828. In case of leakage in any of the retorts so assembled and connected 40 there is no risk of intercommunication with the other retorts.

I will now proceed to describe more particularly and exactly the mode of conducting this process, and describe an apparatus for the 45 purpose, referring in so doing to the drawings annexed and the letters of reference marked thereon.

The drawings show the invention as applied to a locomotive-engine boiler.

50 Figure 1 shows a plan with the furnace or roof crown removed; Fig. 2, a sectional eleva-

tion in the plane indicated by the line $x\ x$ in Fig. 1; Fig. 3, a partial vertical section in the plane indicated by the dotted line $y\ y$ in Figs. 1 and 2. Fig. 4 shows a side elevation with 55 the side wall of the furnace removed; Fig. 5, a front elevation with the front wall of the furnace removed. Fig. 6 shows the combining-tubes in section on an enlarged scale. Figs. 7 and 8 show a modification of the lower 60 part of the furnace, drawn in the same planes of sectional elevation in Figs. 2 and 3. Figs. 9, 10, 11, 12, 13, 14, 15, and 16 show enlarged sections of the apparatus in detail; and Figs. 17, 18, 19, and 20, modifications in form and 65 application of the entire apparatus.

The same letters of reference apply to the same parts in the several figures.

A represents the furnace or combustion-chamber of a locomotive-boiler; A', the metallic 70 wall of the fire-box; A², the surrounding water-space; A³, the flues or tubes leading to the chimney; A⁴, the furnace-crown, and A⁵ the crown-bars. This portion of the apparatus does not materially differ from that in general use, and 75 any other efficient form of furnace, either for steam-generation or metallurgic or other purpose, may be substituted in making useful application of this invention.

The floor of the furnace A is composed of 80 plates B, fitting closely to each other, with proper provision to remain close and tight without cramping or distortion from unequal expansion and contraction. In the floor-plates B are formed a series of tubulures or jet-pipes, B', 85 in the form of truncated hollow cones, the smaller end being upward. The function of these conical jet-tubes B' is to admit the porous, gaseous, or aeriform fuel and the air with which the said fuel is burned, and to heat 90 such air as it passes upward or inward to the combustion-chamber. The jet-tubes B' are preferably arranged at equal distances in parallel rows, for the better distribution of the gas-jets in the furnace, and also for the more convenient connection of the gas supplying and distributing tubes, as will hereinafter appear.

95 Centrally located in each of the tubulures B' are jet-tubes C, made preferably of tips C', having small central conical apertures, and inserted in pillars or tubes C², fitted gas-tight in elbows C³, attached by tubes C⁴ branching

laterally from pipes C⁵. The pipes C⁵ are hermetically closed at the ends C⁶, and at the opposite ends are inserted gas-tight into the pipes C⁷ and C⁸. The pipes C⁵ are arranged horizontally beneath the floor-plates B, in parallel position with each other, between alternate lines of tubulures B', so that each pipe C⁵ supplies the lines of branches and jet-tubes C upon both sides thereof. The lower pipe, 10 C⁸, is larger than the upper pipe, C⁷, and supplies the fuel to the pipes C⁵ under the four outer floor-plates B, while the upper pipe, C⁷, supplies only the two pipes C⁵ under the central pair of plates B, and the short pipes C⁹ 15 under the end of the four outer plates B, toward the right hand in Figs. 1 and 2. The short pipes C⁹ are placed above the pipes C⁵, under the outer plates B, and supply by branches C⁴ jet-tubes C, extending upward 20 into the tube B' under the retorts or generators D' D². The tubes C⁹ are closed at their ends farthest from the pipe C⁷.

D' and D² are retorts or generating-vessels placed a little distance above the plates B and 25 jet-tubes B', over the outer floor-plate B, and as close as may be conveniently arranged toward the wall of the furnace. D³ and D⁴ are smaller retorts or generating-vessels, similarly placed above the jet-tubes B' of the central 30 plate B.

From the upper part of the retorts D' and D³ are tubes D⁵ and D⁶, which unite in the upper end combining-tubes E E, (shown in section in Fig. 6,) consisting of one jet-pipe, E', 35 surrounded by another tube, E², and having in common one delivery or discharge tube, E³. The lower ends of the combining-tubes E E are connected by suitable tubes, E⁴, to the retort D² and D⁴ at their base. A similar series 40 of pipes, D⁷ and D⁸, connect from the upper part of the retorts. D² and D⁴ lead to the pipes C⁷ and C⁸. The retorts D', D², D³, and D⁴ are supported upon pillars F, and held thereon by bolts F' extending through lugs 45 F², cast on the retort, down through the pillars F and plates B, where they are secured by a suitable nut, F⁴. The upper end of the pillars F are formed with jaws F⁵, for the purpose of embracing the lugs F² and better retaining the retorts in position. The pillars F, lugs F², jaws F⁵, and bolts F' and nuts F should be so fitted and adjusted as to permit 50 of the expansion and contraction, and yet to safely retain the retorts in position.

55 Into the retorts D' and D² are fitted pipes G and G', provided with valves G² and G³, leading from a tank containing water or steam under pressure. These pipes G and G' extend through the furnace-wall A' and water-space 60 A², and serve to admit water or steam into the retorts D' and D². Similar pipes H and H', also extending through the furnace-wall A' and water-space A², and provided with suitable valves or stops, H³ and H⁴, connect one of 65 the branches of each of the combining-tubes E E with a vessel, K, containing liquid hydrocarbon or oil under pressure, and serve to in-

duce in regulable quantities a supply of such fluid to the retorts D' and D².

Under each of the tubes C⁵ is placed a trough, 70 L, having perforations in the sides, through which the branches C⁴ extend. The functions of the troughs L are to avoid or to intercept currents of air from cooling the pipes C⁵, and to retard radiation of heat from the said pipes 75 C⁵, and they may be filled for the more effectual retention of heat with a non-conducting or slow-conducting substance, as shown in Figs. 7 and 8. The spaces between the jet-tubes or tubulures B' in the floor-plates B may be similarly covered with non-conducting material, as 80 shown in Figs. 7 and 8.

Upon the floor-plate B, at the part under the retort D³, is formed a rim, M, inclosing a small cavity or basin, M', into which a pipe, 85 N, leading from the oil-reservoir, and provided with a suitable cock or valve, N', terminates. A damper, P, or register for closing off the air-supply under the furnace-floor, is fitted beneath the trough L. 90

The operation of the process with the apparatus is as follows: A lighted match is placed in the cavity M' and a small amount of oil, admitted through the pipe N, is ignited therein, heating the retort D³. At the same time a 95 small supply of water is permitted to flow into the retort D³. Next a small supply of oil is admitted to the retort D⁴. Steam, generated and superheated, issuing from the upper part of the retort D³, passes by the pipe 100 D⁵ to the combining-tube E, where it commingles or combines with the hydrocarbon issuing from the tank containing it under pressure, and discharges it in a finely-divided state 105 into the retorts D⁴ and D², where it is converted into gas at a high temperature, and, passing down to the pipe C⁷, is distributed through the pipes C⁵ through the jets C, carrying air with it through the tubulures B' in the central floor-plates B B, and ignited in the furnace. At 110 the same time that the gas is delivered and ignited with air entering the tubulures B' of the central plates B of the furnace, gas enters through the tubes C⁹ through jets C under the larger retorts D' and D², the ignited gas 115 entering the furnace-chamber with the air through the tubulures B' and floor-plates, and thus heats the air at its entrance to the furnace-chamber, and very soon heats all of the retorts D' D² D³ D⁴ in the furnace. When this 120 takes place oil is admitted to the retort D² and steam or water to the retort D'. As the temperature increases the flame in the furnace, issuing from or entering the tubulures, from being at first of yellow color and luminous 125 becomes a clear blue or purple and transparent, and the entire furnace-chamber is filled with ignited gases of intense temperature. The issuing products of combustion, after passing through the boiler-flues, are transparent, 130 invisible, and almost inodorous.

By means of the valves G² and G³, H³ and H⁴, which, for convenience of manipulation, should have indices and dials or notched sec-

tors, as shown in Figs. 1 and 7, for the purpose of showing and holding them in adjustment. The supply of fuel and temperature can be controlled to meet the varying requirements 5 of work.

The combined effect of steam or water passing into and through the retorts and mingling with the products of oil or hydrocarbon distillation, and thence entering into the inclosed combustion-chamber, is, with a very small fuel consumption, to generate larger volume of heat, of greater intensity, and in a more uniform and reliable manner than is otherwise practicable.

15 The easy adaptability of this apparatus to any form of furnace affords a degree of latitude in planning boiler and engine constructions not found in any other constructions where boilers having furnaces fired in the 20 usual manner are inadmissible. Modifications of this character and of the form and position of the retorts are shown in Figs. 17, 18, 19, and 20.

25 The jets may impinge directly on the heat-absorbing surfaces, as shown in Figs. 17 and 18, or may be so located as to pass into the flues, as in Fig. 19, or the heat-absorbing surfaces may be increased by the introduction of a coil of tube, through which the water of the 30 boiler circulates in the combustion-chamber, as shown in Fig. 20. Such increase of heating-surface does not interfere with perfect combustion of gases as effected by this process and apparatus, although it has often been found 35 to do so with other processes and fuels, the introduction of gaseous fuel and air at high

temperature securing at all times complete combustion.

What I claim as my invention is—

1. In an apparatus for burning hydrocarbon fluids with steam and air, the combination of two or more pairs of separate retorts heated by gases generated therein, so connected by tubes with a hydrocarbon fluid and water or steam supply and with jet-tubes from which 40 the resultant gases or vapors and steam are burned that one retort of each pair shall receive a supply of steam or water, and shall, after superheating such steam therein, discharge it with a hydrocarbon fluid into the 45 other retort of the pair, from which the resultant heated gases or vapors pass to the jet-tubes at the points of combustion in the furnace, substantially as and for the purpose set forth.

2. In an apparatus for burning hydrocarbon fluids with steam and air, the combination of two or more pairs of separate retorts so connected with each other and the steam or water supply and the hydrocarbon-fluid supply and with the gas-distributing pipes and jet-tubes 55 or burners that the steam superheated in one retort of one pair shall enter the second retort of said pair and the gases or vapors, or a portion thereof, generated in such second retort shall supply the heating-jets under both sets 60 of retorts, substantially as and for the purpose set forth.

CHARLES HOLLAND.
